UNITED STATES PATENT OFFICE.

BENJAMIN S. COE, OF BRIDGEPORT, CONNECTICUT, ASSIGNOR TO THE COE-STAPLEY MANUFACTURING COMPANY, OF BRIDGEPORT, CONNECTICUT, A CORPORATION OF CONNECTICUT.

MATCH-BOX.

1,158,118.

Specification of Letters Patent. Patented Oct. 26, 1915.

Application filed October 8, 1914. Serial No. 865,658.

To all whom it may concern:

Be it known that I, BENJAMIN S. COE, a citizen of the United States, residing at Bridgeport, county of Fairfield, State of Connecticut, have invented an Improvement 5 in Match-Boxes, of which the following is a specification.

This invention has for its object to provide boxes or carriers for strips of card- 10 board matches, having scratchers, which shall be neat and attractive in appearance and so simple and inexpensive to produce that they may be given away as a means of advertisement, the boxes at the same time 15 being strong and durable and adapted for long continued use.

In order to accomplish this result, I have devised a box comprising two members, both of which may be struck up complete from 20 sheet metal, for example aluminum, one of said members being adapted to slide within the other and said members being connected together so that when extended they may be swung into a position at an angle to each 25 other without detachment and without the use of rivets or a hinge joint.

In the accompanying drawing forming a part of this specification, Figure 1 is a perspective of the box in the closed position; 30 Fig. 2 a perspective showing the members in the extended position; Fig. 3 a perspective showing the members turned at an angle to each other; Fig. 4 a perspective of the cover member detached, and Fig. 5 is 35 an elevation of the box member detached.

10 denotes the box member and 11 the cover member. The box member comprises a bottom, ends and sides, blanked out and formed from sheet metal, one end being 40 appreciably higher than the other end and the edges of the sides forming inclines from end to end. The sides are provided at one end with bumps 12 and at their edges at the same end with lips 13 which are folded over 45 parallel with the bottom to serve as retaining means for a strip 14 of cardboard matches, the end of the scratcher 15 being slid under the lips to retain the strip in place, as clearly shown in Figs. 2 and 3. 50 The cover member is open at both ends and comprises a top and sides which form inclines corresponding with the sides of the box member. The sides of the cover member are provided with longitudinal grooves 55 16 which receive the bumps 12 upon the box

member, the bumps sliding freely in the grooves and the ends of the grooves serving as stops when engaged by the bumps to limit the extending movement of the members. The sides of the cover member are additionally provided with inturned flanges 17 which act to retain the box member securely against movement when in the closed position, the height of the inclined sides of the box member being just sufficient to cause the edges thereof to be frictionally held by the flanges of the cover member when in the closed position. The ends of the flanges are cut away, leaving shoulders 18 which serve as abutments against which the end of the bottom of the box member rests when in the fully open position, as in Fig. 3. Both members are provided with corrugations 19 for convenience in engagement by the fingers of the operator in opening and closing. The members are assembled by simply opening the sides of the cover member outward slightly, passing the box member into the open end of the cover member and springing the bumps into engagement with the grooves. The operation in opening is simply to slide the box member and cover member in opposite directions, that is, from the position shown in Fig. 1 to that in Fig. 2, and to then swing the members to the position shown in Fig. 3, in which the inner end of the bottom of the box member is abutting against the shoulders on the cover member, thus retaining the members perfectly rigid in striking a match. In closing, the members are first moved from the position shown in Fig. 3 to that shown in Fig. 2, and then the box member is slid into the cover member, as in Fig. 1. The operations of opening and closing the box may be performed either by one hand, using the thumb and first and second fingers, or with both hands, as preferred.

Having thus described my invention I claim:

1. A box of the character described comprising a cover member having a top, and sides provided with longitudinal grooves, and inturned flanges the ends of which are cut away leaving shoulders, and a box member having bumps adapted to engage the grooves and slide therein, said box member being adapted when extended to be turned at an angle to the cover member with the back thereof abutting against the shoulders.

2. A box of the character described comprising a cover member having inclined sides provided with longitudinal grooves, and inturned flanges the ends of which are 5 cut away leaving shoulders, and a box member having inclined sides adapted to engage the flanges in the closed position and bumps adapted to engage the grooves and slide therein, said box member being adapted 10 when extended to be turned at an angle to the cover member with the back thereof abutting against the shoulders.

3. A box of the character described comprising a cover member having a top, and

sides provided with longitudinal grooves 15 and inturned flanges and a sliding box member having bumps adapted to engage the grooves, the sides of said members inclining from end to end and the edges of the sides of the box member engaging the flanges on 20 the cover member to frictionally hold said members in the closed position.

In testimony whereof I affix my signature in presence of two witnesses.

BENJAMIN S. COE.
